FIG. 1

FIG. 2 → IV

→ IV

FIG. 4

FIG. 3

FIG. 1 is a front perspective view of the bathtub wall unit embodying my new design, showing the seat and shelf in their closed positions;

FIG. 2 is a front elevational view thereof showing the seat and shelf in their open positions;

FIG. 3 is a top plan view of FIG. 2; and

FIG. 4 is a cross-sectional view taken on line IV-IV of FIG. 2. The broken line representation of a bathtub in the figures is for purpose of illustration only.

I claim:

The ornamental design for a bathtub wall unit, substantially as shown and described.
